The ornamental design for an orthopaedic washer, as shown and described.

DESCRIPTION

FIG. 1 is a perspective view of an orthopaedic washer

showing our new design;

FIG. 2 is a bottom plan view thereof;

FIG. 3 is a side elevational view thereof;

FIG. 4 is a top plan view thereof;

FIG. 5 is a cross-sectional view thereof taken along lines

5—5 of FIG. 2; and,

FIG. 6 is an end elevational view thereof.

The broken line showing of the screw member in FIG. 3 is for illustrative purposes only and forms no part of the claimed design.
